Patented Nov. 5, 1968

212,656

INDOOR CHARCOAL GRILL

Russell E. Ihde, 1116 Maple St.,
Neenah, Wis. 54956

Filed Jan. 8, 1968, Ser. No. 10,086

Term of patent 14 years

(Cl. D81—10)

FIG. 1

FIG. 3

FIG. 2

FIGURE 1 is a perspective view showing my new design for an indoor charcoal grill;

FIGURE 2 is a rear elevational view thereof;

FIGURE 3 is a side elevational view thereof, and the side opposite being a mirror image; and

FIGURE 4 is a top plan view of the same.

I claim:

The ornamental design for an indoor charcoal grill, substantially as shown and described.
